UNITED STATES PATENT OFFICE.

EDWARD F. CALDWELL, OF NEW YORK, N. Y., ASSIGNOR TO THE PHOENIX
GLASS COMPANY, OF PITTSBURG, PENNSYLVANIA.

DESIGN FOR A GLOBE OR SHADE.

SPECIFICATION forming part of Design No. 26,647, dated February 16, 1897.

Application filed January 13, 1897. Serial No. 619,130. Term of patent 7 years.

To all whom it may concern:

Be it known that I, EDWARD F. CALDWELL, a citizen of the United States, residing at New York, in the county of New York and State of New York, have invented a certain new and useful Design for a Globe or Shade; and I do hereby declare the following to be a full, clear, and exact description of the invention, such as will enable others skilled in the art to which it appertains to make and use the same.

This invention has relation to designs for gas, electric-light, and lamp globes and shades; and it consists in the shape and ornamental configuration herein shown and described.

In the accompanying drawings, Figure 1 is a plan view, and Figs. 2 and 3 are side views, of a globe embodying my novel design.

The body of the globe is pear-shaped, ornamented with a series of alternating flutes *a* and rounded or bellied panels *b*, both of which may be appropriately etched. The upper edge of the globe is beveled interiorly coincident with the surface of a cone, the resultant effect being a scalloping or rounding of the flutes and panels, as shown.

What I claim as my invention is—

The design for a globe or shade, substantially as shown and described.

In testimony whereof I have affixed my signature in presence of two witnesses.

EDWD. F. CALDWELL.

Witnesses:

ANDREW M. BROWN,
R. MEYER.
